APPARATUS FOR FACE SATURATING POROUS MATERIALS IN THE MANUFACTURE OF HARD SURFACE FLOOR COVERINGS

Leon E. Crew, Elmhurst, Del., assignor to Delaware Floor Products, Inc., Wilmington, Del., a corporation of Delaware

Application January 14, 1936, Serial No. 59,037

2 Claims. (Cl. 91—51)

The present invention relates to the treatment of relatively porous material made from wood pulp or the like in strips several feet in width and of indeterminate length preparatory to application thereto of a colored decoration in the manufacture of hard surface floor coverings, or in some instances during the application of coloring matter to one surface thereof.

In the production of hard surface floor coverings of certain types, it has heretofore been the usual practice to initially "saturate" a strip of the porous material used as a base by passing it through a body of a suitable saturating fluid, and to then subject it to the action of squeeze rollers to force the fluid into the base as well as to remove any excess of the fluid therefrom. The saturated base, while it is still wet with the fluid, then passes to a printing machine or the like operative to apply to one face thereof the desired colored ornamentation, the miscibility of the printing dyes or other coloring matter with the saturating fluid facilitating the penetration of the former into the base for an appreciable depth from the printed face.

This practice is open to certain objections, among which is the tendency of the base when its opposite faces are wet with the saturating fluid to stick to the printing machine instead of moving freely therethrough; the tendency of quantities of the saturating fluid to adhere to the bed of the machine through contact therewith of the back face of the material while wet with the fluid, thus necessitating frequent cleaning to prevent interference with satisfactory operation of the machine; and the absorption, because of passage of the base through a body of the fluid, of larger quantities thereof than required for best results, the entire thickness of the base often becoming completely saturated, although penetration of the fluid thereto for only a relatively small distance from one face is all that is required for proper ornamentation of that face.

My invention is therefore designed to provide improved apparatus for effectively saturating or impregnating one face of a porous base material to a desired depth sufficient to assure suitable penetration of coloring matter thereto while maintaining the opposite face and the material lying adjacent thereto free or virtually free of saturating fluid and thus substantially in its normal or dry state, whereby contact of appreciable quantities of the saturating fluid with the bed of the machine is prevented so it can be kept clean, dry and free from contamination thereby at all times.

Moreover, with the aid of my invention the quantity of fluid saturant supplied to and absorbed by the base material may be subjected to exact control and the extent of its penetration thereto from the surface to which it is applied can thus be regulated so as to obtain the most satisfactory and economical results.

It is therefore a principal object of the invention to provide means for progressively saturating one face of a strip of porous material and effecting penetration of the saturating fluid into the strip to a desired depth from said face, while maintaining the remainder of the strip substantially free of the fluid.

Other objects, purposes and advantages of the invention will hereinafter more fully appear or will be understood from the following description of apparatus constructed in accordance therewith reference being had to the accompanying drawing, in which:

Fig. 1 is a more or less diagrammatic longitudinal section of the said apparatus;

Fig. 2 is a side elevation of a portion thereof showing means for maintaining a body of the saturating fluid in contact with the surface of the saturating roller;

Fig. 3 is a fragmentary top plan view of the apparatus shown in Fig. 2; and

Fig. 4 is a fragmentary side elevation of the main driving gears of the machine.

Like characters of reference are used throughout the drawing to designate the same parts.

In saturating one face of a strip of porous base material with the aid of apparatus embodying my invention, I first preferably subject the strip to mild heating as it is progressively drawn from a roll or the like and then while it is still warm continuously apply to one of its faces a film of suitable saturating fluid, desirably by transferring the fluid to the strip from a moving surface to which the fluid is supplied in a continuous, substantially uniform film. The surface carrying said film is preferably moved at a somewhat higher speed than the strip at the point of engagement therebetween so that an adequate supply of the fluid to the strip is assured, and the latter is then subjected to severe rolling pressure whereby the fluid is caused to penetrate into the pores of the strip for an appreciable depth below the face to which it was applied. Thereafter, if the strip is to be printed, it is at once led to the printing machine while its fluid impregnated face is still wet and printing of such face is then carried out in the usual way and followed by drying and other customary steps.

In manufacturing solid color floor coverings, however, I have found the printing step may be dispensed with entirely when the saturating fluid applied to the strip in the manner just described is first suitably colored with the necessary pigments as the strip may be dried immediately after being subjected to rolling pressure to effect the proper degree of penetration of the colored saturant, or after the front face is saturated 10 with the latter the back face may be saturated with uncolored saturant or other suitable fluid before the strip is finally dried.

I shall now refer more particularly to the machine shown in the drawing which is constructed 15 in accordance with the invention and eminently suitable for the performance of the operations I have mentioned, it being understood, however, that for clearness of illustration certain mechanical elements generally employed in machines of this general character, such for example as journal bearings and supports therefor, driving mechanism and other well known devices have been omitted as they may be of any desired character or type suitable for their intended functions; it will thus be understood their 20 specific form and/or arrangement are merely matters of convenience or preference.

The said machine which may best be described 25 with reference to the progress of a strip there-through while being subjected to the aforesaid treatment, comprises a pair of horizontally disposed idle rollers 1, 2 beneath which the strip S is conducted in its passage from a roll or other suitable source (not shown). Beneath the portion 30 of the strip extending between these idle rollers is disposed a shield 3 open at the top and closely underlying the strip through which extend a plurality of steam pipes 4 or other heating means effective to warm the strip, preferably to a temperature of about 100° F., as it passes 35 thereover. The warmed strip thereafter passes upwardly over an idle roller 5 and thence angularly rearwardly and downwardly beneath an idle roller 6 and rearwardly and upwardly over a 40 saturating roller 7 desirably about 8½" in diameter and in length at least equal to the width of the strip. This positioning of these several rollers as well as that of others hereinafter more 45 specifically mentioned, affords the desired support to the strip and permits the machine to be constructed as a compact unit, but it will be understood they may be otherwise arranged if desired as long as they are so positioned as to properly 50 perform their respective functions.

A trough 10 supported beneath the saturating roller 7 maintains a body of saturating fluid F in contact with the lower portion of this roller, while an adjustable doctor blade 11 extends across the face of the roller between the fluid F and the strip S at its point of contact with the roller thereby permitting accurate control of the thickness of the film of fluid carried by the roller to the strip during its rotation in engagement therewith.

From the saturating roller 7 the strip passes 55 angularly rearwardly and downwardly beneath an idle roller 14 and thence between a pair of squeeze rolls 15, 16 operating at equal rotational speed determinative of the linear speed of the strip and exerting a controlled rolling pressure thereon. Since devices of many different types are known for regulating the pressure exerted by pressure rolls of this general character on a strip passing between them, no specific description 60 of mechanism suitable therefor is herein re-

quired and none is shown in the drawing; it is preferable, however, that such mechanism be of a character permitting the gears 17, 18 by which one roll is driven from the other to be maintained continuously in mesh at any adjustment thereof likely to be demanded by operating conditions.

Suitable roll driving mechanism (not shown) is connected, desirably through a pinion 19, with gear 17 for driving roll 15, for example, at a 10 peripheral speed of 26 feet per minute and the gear 18, meshing with gear 17, thus drives roll 16 at the same speed, the combined action of these rolls on the strip moving it through the machine at a corresponding linear speed. 15

When the strip is thus driven by the squeeze rolls at a linear speed of approximately 26 feet per minute it is preferable that the saturating roller 7 be driven, by mechanism now to be described, at a peripheral speed of approximately 20 31 feet per minute, but when other speeds are employed it is desirable that approximately this ratio, 26:31, be fairly closely adhered to, so as to maintain a small body of the saturating fluid f in contact with roller 7 and the adjacent face 25 of the strip just in advance of the area of most intimate engagement therebetween whereby an adequate supply of saturating fluid to that face is assured.

For driving roller 7 at the desired speed, the 30 shaft of roll 15 is provided with a sprocket 20 for the reception of a chain 21 running over another sprocket 22 carried by the shaft of roller 7, and the size of these sprockets is preferably proportioned so as to maintain approximately the ratio 35 26:31 between the peripheral speeds of the rollers for the reasons to which reference has been made.

The shaft of the other squeeze roll 16 is provided with a somewhat similar sprocket 23 for the 40 reception of a chain 24 which chain drives a larger sprocket 25 on the shaft of a drum 26 above and forwardly of the squeeze rolls. The strip, after its passage between the latter, reverses its 45 direction of travel and passes upwardly and forwardly over this drum, from which it may be fed directly to the printing machine or other mechanism (not shown) by which it is to be further operated upon.

The pressure to which the strip is subjected by 50 the squeeze rolls forces the saturating fluid well into its pores to the desired depth from the face to which it is applied, but preferably not so far as to wet the opposite face of the strip, the pressure exerted by the squeeze rolls being suitably 55 regulated to effect this result.

The saturating fluids usually employed are often slightly tacky after application to the strip, and some of the fluid may adhere to squeeze roll 15 as the strip passes thereover. A cleaning blade 60 27 is therefore so positioned as to bear against the roll surface and continuously scrape therefrom any fluid or other material adhering thereto.

Mention has been made of means for supplying the saturating fluid to saturating roller 7, comprising a trough 10. This trough is desirably of slightly greater length than roller 7 and may be substantially rectangular in horizontal section. As best shown in Figs. 2 and 3, adjacent each end of the trough is a pair of vertically and horizontally offset rollers 30, 31 adapted to support the trough in a substantially horizontal position beneath roller 7 upon inclined rails 32, one rail being disposed at each side of the machine and extending downwardly and rearwardly from the 70 75

vicinity of roller 7 to permit the trough to be lowered along the rails to the rear of the machine when it is desired to remove it therefrom for cleaning or the like. A latch 33 may be provided adjacent each end of the trough to engage the upper end of the corresponding rail and releasably maintain the trough in fluid feeding relation to roller 7.

While I have herein described certain mechanism adapted for the purposes of my invention and constructed in accordance therewith, it will be understood that changes and modifications in the form, construction and arrangement of the several elements of the said mechanism and in their mode of operation will readily occur to those skilled in the art and may be made if desired without departing from the spirit and scope of the invention as defined in the appended claims.

Having thus described my invention, I claim and desire to protect by Letters Patent of the United States:

1. In a machine of the class described, a saturating roller rotatable on a horizontal axis, a trough disposed beneath said roller adapted to

contain a fluid in contact with the roller surface, a pair of inclined rails respectively disposed adjacent opposite ends of the trough, means projecting outwardly from the ends of the trough adapted to movably engage said rails to support the trough therefrom, and releasable means for restraining said last mentioned means from movement relatively to the rails when the trough is in position to effect contact between its contained fluid and the saturating roller.

2. In a machine for face saturating a strip of floor covering felt, a saturating roller rotatable on a horizontal axis and adapted to engage one face of the moving strip, a trough beneath the roller adapted to maintain saturating fluid in contact with the roller surface, a pair of inclined parallel rails disposed adjacent the ends of the trough, means movable along the rails for supporting the trough therefrom and releasable means for maintaining the trough in fixed position relatively to the roller to maintain said fluid in contact therewith.

LEON E. CREW.
